Primary Examiner — Amy C Wierenga

Assistant Examiner — Kathryn Elizabeth Zieno

(57) **CLAIM**

The ornamental design for a hand shower, as shown and described.

DESCRIPTION

FIG. 1 is a top view of a hand shower showing my new design;

FIG. 2 is a bottom view thereof;

FIG. 3 is a left side view thereof;

FIG. 4 is a right side view thereof;

FIG. 5 is a front view thereof;

FIG. 6 is a back view thereof;

FIG. 7 is a top perspective view thereof;

FIG. 8 is a bottom perspective view thereof; and,

FIG. 9 is an enlarged detailed view of the portion of the hand shower encircled at 9 in FIG. 1.

The dot dash broken line indicates cutoff boundaries for enlarged detailed portion views and form no part of the claim.

The evenly spaced broken lines depict portions of hand shower that form no part of the claim.

1 Claim, 9 Drawing Sheets
